UNITED STATES PATENT OFFICE.

CHARLES SCHAEFER, OF TOLEDO, OHIO.

SHOE-LAST.

1,141,584.

Specification of Letters Patent.

Patented June 1, 1915.

Application filed August 8, 1914. Serial No. 855,876.

To all whom it may concern:

Be it known that I, CHARLES SCHAEFER, a citizen of the United States, residing at Toledo, in the county of Lucas and State of Ohio, have invented new and useful Improvements in Shoe-Lasts, of which the following is a specification.

- My invention relates to new and useful improvements in shoe lasts, and has for its object to provide an exceedingly simple and effective construction by which the lower portion of the last is so jointed as to permit of bending the last to facilitate the building up of cork soles on the inside of a shoe.
- With these ends in view this invention consists in the details of construction and combination of elements hereinafter set forth and then specifically designated by the claims.
- In order that those skilled in the art to which this invention appertains, may understand how to make and use the same, I will describe its construction in detail, referring by numeral to the accompanying drawing forming a part of this specification, in which—

Figure 1, is a side elevation of a last made in accordance with my improvement, showing a series of figures thereon, as a guide in reckoning the measurements of the shoe. Fig. 2, is a plan view with the locking block removed; and Fig. 3, is a bottom plan view.

In carrying out my invention as here embodied 1 represents the body of the last including the heel and arch thereof, while 2 represents the toe of the last which is jointed to the former by the hinge 3. This permits the toe of the last to be set at any desired angle relative to the body thereof, and when so set the two are locked and held rigidly in position by the metal strap 4 which is nailed or screwed to the two sections across the joint, as clearly shown in Fig. 3, and in order that the setting of the last may be absolutely rigid, a wedge 5 is inserted between the two sections as clearly shown in Figs. 1 and 3, which wedge is held in place by the metal strap 4.

The instep 6 of the last sets in place in the usual manner, completing the last and gives further rigidity to the structure.

The series of figures on the side of the

last are used to designate the position of deformities in a person's foot and correspond to similar figures on a foot and last measure and also to figures in the measure chart or book. In practice the foot and last measure is placed upon the person's foot and a tape measure placed over the foot at the different positions designated by figures on the foot and last measure corresponding to the figures on the last, thereby giving the measurements of the deformities at these positions to enable the shoe maker to properly position the last and add the necessary cork or protuberances thereto in the proper locations.

By the use of my improvement much time and expense is saved in the making of cork sole shoes and a much better result is produced since the cork is built upon the inside of the shoe instead of the outside.

Of course I do not wish to be limited to the exact details of construction as here shown, as these may be varied within the limits of the appended claims without departing from the spirit of my invention.

Having thus fully described my invention, what I claim as new and useful, is—

1. As a new article of manufacture a shoe last having the toe thereof hinged to the body provided with a wedge for holding the two parts at their proper relative angles, and a metal strap for holding these parts in their adjusted position.

2. In a shoe last the combination of a body, a toe piece hinged thereto, a wedge for determining the adjustment between the two sections, and a metal strap for holding the sections in their adjustment as specified.

3. In a shoe last the combination of a body, a toe piece hinged thereto, a wedge for determining the adjustment between the two sections, a metal strap for holding the sections in their adjustment as specified, and an instep section adapted to cover the hinge and complete the shape of the last as specified.

In testimony whereof, I have hereunto affixed my signature in the presence of two subscribing witnesses.

CHARLES SCHAEFER.
